UNITED STATES PATENT OFFICE.

ANDREW L. HATFIELD, OF HILLSIDE, NEW JERSEY.

WASHING APPARATUS OR THE LIKE.

1,208,706.

Specification of Letters Patent. Patented Dec. 12, 1916.

Application filed February 5, 1916. Serial No. 76,255.

To all whom it may concern:

Be it known that I, ANDREW L. HATFIELD, a citizen of the United States, residing at Hillside, in the county of Union and State 5 of New Jersey, have invented certain new and useful Improvements in Washing Apparatus or the like; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

15 The present invention has reference, generally, to improvements in washing machines; and, the invention relates, more particularly, to a novel construction of machine for automatically washing clothes and similar articles and fabrics without necessity of employing manual labor.

The present invention has for its principal object to provide a novel construction of apparatus by means of which soil and 25 dirt may be quickly removed from clothes and fabrics without injury to the most delicate and sheer fabrics, and without employing mechanical stirrers, beaters, rubbers or other mechanical movements, and without 30 requiring any tiresome manual labor or manipulation of either the clothes or the novel apparatus.

A further object of the present invention is to provide an automatic washing apparatus in which the soiled clothes or other fabrics are placed and submerged in water, a novel means being provided in said apparatus for agitating the clothes and water by air to carry the latter, together with a 40 suitable cleansing agent such as soap, into intimate and dirt freeing contact with the former.

Other objects of the present invention, not at this time more particularly enumerated, 45 will be clearly understood from the following detailed description of the present invention.

With the various objects of my present invention in view, the same consists, primarily, 50 in the novel construction of washing apparatus hereinafter set forth; and the invention consists, furthermore, in the novel arrangements and combinations of the various devices and parts, as well as in the details 55 of the construction of the said parts, all of which will be more fully described in

the following specification, and then finally embodied in the claims which are appended to and which form an essential part of said specification.

60 The invention is clearly illustrated in the accompanying drawings, in which:—

Figure 1 is a vertical longitudinal section of the novel washing apparatus made according to and embodying the principles of 65 my present invention. Fig. 2 is a longitudinal cross section of the same, taken on line 2—2 in said Fig. 1, looking downward. Fig. 3 is a detailed vertical longitudinal section of a two-way valve employed as a part 70 of the novel construction of washing apparatus.

Similar characters of reference are employed in all of the hereinabove described 75 views to indicate corresponding parts.

Referring now to said drawings, the reference character 1 indicates a suitable standard or supporting frame-work upon which my novel washing apparatus is carried. Secured to and supported upon said standard 80 or frame-work 1 is a tank or tub 2, the upper open end of which is closed, when in use, by a suitable cover-member 3. If desired said tank or tub 2 may be provided with a water inlet-pipe 4, suitably connected 85 therewith, said inlet-pipe 4 being in communication with the water supply mains, but where the apparatus is to be used in places having no water supply or plumbing connections, said inlet-pipe 4 may be omitted, 90 the tank or tub 2 being in such cases filled by hand, as will be understood. Connected with the bottom 5 of said tank or tub 2 is a water outlet or drain pipe 6 for emptying the same, and if desired such outlet or drain 95 pipe 6 may be provided with the closing valve 7, or an ordinary stopper may be used to close the same against the passage of the water from the tank or tub 2. It will also be understood that said outlet or drain pipe 6 100 may be connected directly with a soil-pipe of a plumbing system where such plumbing is present.

The reference character 8 indicates a horizontal shelf or platform located beneath said 105 tank or tub 2 and suitably supported by being properly connected with said standard or supporting frame-work 1. Located suitably upon said shelf or platform 8 is a pump mechanism 9 of any desirable construction, 110 (the kind of pump illustrated in the drawings being of the centrifugal or rotary type,

although I do not desire to limit myself to such type, since many other types of pump construction are both available and possible of use in connection with my novel washing apparatus). Also supported upon said shelf or platform 8 is an electric motor 10, or other prime mover or power element, the power pulley 11 of which is connected operatively by a belt 12, or other suitable 10 transmission, to the driving-pulley 13 of said pump mechanism 9.

The reference character 14 indicates a stand pipe which passes through and is suitably secured to the bottom 5 of said tank or 15 tub 2, so that the said stand pipe extends upwardly through the interior of said tank or tub 2, and at one side thereof, to a point above the water line thereof, its upper end being closed by a cap 15 or otherwise. Connected 20 with the lower end of said stand pipe 14 and in communication therewith is a laterally extending header-pipe 16, the same being disposed so as to rest upon supporting blocks 17 on the bottom or floor of said 25 tank or tub 2 and within the same. Supported in like manner upon the opposite side of the bottom or floor of said tank or tub 2 is another laterally extending header pipe 18. Each header pipe 16 and 18 is provided 30 with a plurality of transversely projecting coupling-necks 19 to opposite units of which are connected transverse air discharge pipes 20 provided in their upper sides with a plurality of spaced discharge perforations or 35 small air outlets 21. Said header pipes 16 and 18 with the interconnecting air discharge pipes 20 provide an air discharge means which substantially covers the entire area of the bottom or floor of said tank or tub 2, and the purposes or operation 40 of which will be subsequently described. Extending upwardly and telescopically through the interior of said stand-pipe 14 is an air delivery pipe 22 which terminates 45 short of the closed upper end of said stand pipe but above the water-line of the interior of said tank or tub 2. Said air delivery pipe 22 is of smaller diameter than the interior diameter of said stand-pipe so that an 50 air passage 23 is provided between said air delivery pipe 22 and the interior sides of said stand pipe 14 which leads into said header pipe 16. Connected with the lower end of said air delivery pipe 22 is an air supply pipe 24; and the exterior lower end 55 of said stand-pipe 14 is coupled mechanically by a suitable coupling device 25 with said air supply pipe 24, but said lower end of said stand-pipe does not communicate 60 with said air supply pipe 24 except by means of and through said air delivery pipe 22 which alone communicates directly with said air supply pipe 24. Said air supply pipe 24 is connected with the discharge end 26 of 65 said pump mechanism 9, and connected in

the line of said air supply pipe so as to form a part of the conduit thereof is a heating coil 27, the purpose of which will be presently disclosed. Said heating coil is preferably inclosed in a casing 28 having at its 70 upper end ventilating openings 29. Supported upon said shelf or platform 8 beneath said heating coil 27 and within said casing 28 is a heating unit 30, such as a gas or other burner, by means of which heat 75 may be applied to said coil 27.

Connected with the intake end 31 of said pump mechanism 9 is an air pipe 32, the same extending upwardly at one side of said tank or tub 2, and preferably exteriorly 80 thereof, the intake end 33 of said air pipe 32 extending through the side wall of said tank or tub 2 so as to communicate with the interior of the latter above the water line thereof. Connected in the line of said air 85 pipe 32 is a two-way valve 34 having a vertically disposed air inlet passage 35 and an opposite outlet passage 36 both of which communicate with the conduit formed by said air pipe. Said two-way valve is additionally provided with a laterally extending water inlet passage 37, with which communicates a water pipe 38, the intake end 39 of which extends through the bottom 5 of said tank or tub 2, so as to communicate with 90 the interior thereof and receive water therefrom. The rotary valve element 40 of said two-way valve 34 is provided with a diametric valve passage 41, and a laterally extending branch valve passage 42 which 95 communicates with said diametric valve passage 41 at right angles thereto. As will be apparent from an inspection of Fig. 3 of the drawings, when said diametric valve passage 41 stands vertically it affords an 100 uninterrupted passage through the air pipe 32 the body of said valve element closing said water inlet passage 37, but when said valve element 40 is given a quarter turn to the right, by means of the exterior hand-lever 43, one end of said water inlet passage 37 and said branch valve passage 42 is registered with said outlet passage 36 of the valve, the body of said valve element closing said air inlet passage 35, consequently water 115 from the tank or tub 2 is fed to said pump mechanism 9 and is then discharged again into said tank or tub 2 through the air discharge pipes above described, for purposes subsequently to be set forth.

Having thus described the mechanical construction of my novel washing apparatus, I will now describe the manner of its use and its operation when in use.

First the tank or tub 2 is supplied with 125 water, preferably hot water, the same filling the interior thereof to within a short distance of the top, leaving, however, an air-space 44 above the water level. A wooden frame 45 composed of spaced slats is pref- 130

erably placed in the bottom of the tank or tub 2 so as to extend over said air discharge pipes 20. The dirty and soiled clothes or other fabrics 46 are placed in the 5 water contained in the tank or tub 2 and are prevented from contacting with said air discharge pipe 20 by said wooden frame 45. Since the outlet of the air delivery pipe 22 is above the water-line it will be apparent 10 that no water can get into the air circulatory system through such delivery pipe 22. A proper quantity of soap is placed in the water, liquid soap being a very good form of soap for introduction therein. The cover- 15 member 3 of the tank or tub 2 is then fastened down over the top of the latter, after a wooden frame 47, composed of spaced slats, has been placed on the surface of the water to prevent the clothes or 20 fabrics 46 from riding out of the water into said air-space 44. The two-way valve 34 is so set as to close the water pipe 38, and open communication through the air pipe 32 between the air-space 44 of the tank or 25 tub 2 and the pump-mechanism 9. The pump mechanism 9 is now placed in operation, and the same draws air from the air-space 44, and sends the same through the air supply pipe 24 and air delivery pipe 22 30 down through the stand-pipe 14 and into the air discharge pipes 20, whence it is discharged into the water at the bottom of the tank or tub 2 through the small air outlets 21. The air upon being thus discharged 35 into the water, rises therein in streams of air bubbles, which not only agitate the water and the clothes or fabrics 46 therein, but tend to work through the texture of the clothes or fabrics until they reach the 40 surface of the water and break out into the air space 44. This agitation of the water and the clothes therein causes the soapy content of the water to be carried to the surface, whereupon the agitation of the surface water and soapy content produces a 45 steadily augmented suds 48 which forms and piles up on the surface of the water and substantially fills the air space 44. This suds 48 is carried into the air pipe 32 so that 50 the air passage to and through the above described circulatory system of pipes has admixed therewith a soapy moisture, which is in turn discharged from the small air outlets 21 forming additional streams of rising 55 air bubbles carrying with them a soapy film, which is worked into and through the texture of the clothes or fabrics 46 by the rising air bubbles with dirt liberating effect. The above described operation may be continued 60 until the clothes or fabrics 46 are entirely freed from dirt and soil, such results being quickly obtained and in such a manner that the texture of the most delicate fabrics is not in the least injured, as 65 would be most likely where mechanically

operated agitating elements, stirrers or beaters are used.

After the washing operations have been completed, as above described, the dirty water may be removed from the tank or tub 70 2, and clean hot water introduced therein. Thereupon the two-way valve 34 is turned to shut off the air-pipe 32 above the same and connect with the circulating pipe system the water-pipe 38 so that the pump-mechanism 9 will pump water from the tank or tub 2 and discharge the same through the air discharge pipes 20, thus forcing the same up through the clothes in order to 75 rinse the same, this circulation of the water 80 being continued until the clothes are thoroughly rinsed. If it is desired to keep the rinsing water thus circulated hot, the heating unit 30 beneath the heating coil 27 is ignited so that the water as delivered from 85 the pump-mechanism 9 will be reheated while passing through the heating-coil. It may be also mentioned that bluing may be introduced into the rinsing water if desired.

The rinsing water may be drained from 90 the tank or tub 2, and the same left empty of water, and then the air circulation introduced again with drying effect upon the clothes, and if desired the drying air may be heated as it passes through the heating- 95 coil 27 by igniting the heating unit 30.

It will be understood that I do not limit myself to the exact construction and arrangement of the air discharge pipes 20 as shown in the drawings, since the same 100 may be formed in a flat spiral coil or in any other form providing a substantial area of discharge points.

I am also aware that some changes may be made in the general arrangements and 105 combinations of the various devices and parts of my novel washing apparatus, as well as in the details of the construction of the said parts, without departing from the scope of the present invention as set forth in the foregoing specification, and as defined in the 110 claims which are appended thereto. Hence, I do not limit myself to the exact arrangements and combinations of the devices and parts as described in the said specification, 115 nor do I confine myself to the exact details of the construction of the said parts as illustrated in the accompanying drawings.

I claim:—

1. A washing apparatus, comprising a covered tank, an air discharge means at the bottom of said tank, a circulating supply pipe, a pump mechanism connected in the line of said supply pipe, the intake end of said supply pipe communicating with the 120 upper end of the interior of said tank, and the outlet end of said supply pipe communicating with said air discharge means, a water pipe connected with said supply pipe on the intake side of said pump mechanism, 125 130

the intake end of said water pipe communicating with the lower end of said tank, and a two-way valve located at the juncture of said water pipe with said supply pipe.

- 5 2. A washing apparatus, comprising a tank, a standpipe extending upwardly through said tank to a point above the normal water level of the tank, said stand-pipe being closed at its upper end, discharge
10 piping connected with and communicating with the lower end of said stand-pipe, said discharge piping being submerged in and supported upon the bottom of said tank and provided with a multiplicity of upwardly
15 directed spaced openings distributed coextensively with the area of said tank-bottom, a delivery pipe of smaller diameter extending upwardly through said stand-pipe its open upper end terminating short of the
20 closed upper end of said stand-pipe but above the normal water level of the tank, a downwardly extending passage being provided by said stand-pipe between its walls and the exterior of said delivery pipe, and
25 means connected with the lower end of said delivery pipe for supplying a stream of air thereto and thence through said stand-pipe to said discharge piping.

3. A washing apparatus, comprising a
30 tank, a stand-pipe extending upwardly through said tank to a point above the normal water level of the tank, said stand-pipe being closed at its upper end, discharge piping connected with and communicating with the lower end of said stand-pipe, said discharge piping being submerged in and supported upon the bottom of said tank and provided with a multiplicity of upwardly directed spaced openings distributed coexten-
35 sively with the area of said tank-bottom, a delivery pipe of smaller diameter extending upwardly through said stand-pipe its open upper end terminating short of the closed upper end of said stand-pipe but above the normal water level of the tank, a downwardly extending passage being provided by said stand-pipe between its walls and the exterior of said delivery pipe, a circulating supply pipe, a pump mechanism connected in the line of said supply pipe, means for driving said pump mechanism, the intake end of said supply pipe communicating with the upper end of the interior of said tank, the outlet end of said supply pipe communicating with the lower end of said delivery pipe, a heating-coil connected in the line of said supply pipe on the outlet side of said pump-mechanism, a heating-unit mounted beneath said heating-coil, a water pipe connected with said supply pipe on the intake side of said pump mechanism, the intake end of said water pipe communicating with the lower end of said tank, a two-way valve located at the juncture of said water pipe with said supply pipe, and a cover-member for closing the open upper end of said tank.

said heating-coil, a water pipe connected with said supply pipe on the intake side of 60 said pump mechanism, the intake end of said water pipe communicating with the lower end of said tank, a two-way valve located at the juncture of said water pipe with said supply pipe, and a cover-member for 65 closing the open upper end of said tank.

4. A washing apparatus, comprising a tank, a stand-pipe extending upwardly through said tank to a point above the normal water level of the tank, said stand-pipe 70 being closed at its upper end, a lateral header-pipe connected with and communicating with the lower end of said stand-pipe at the bottom of said tank, a second lateral header-pipe transversely opposite said first 75 mentioned header-pipe, a plurality of transversely extending discharge pipes communicating at their opposite ends with said respective header-pipes, said discharge pipes each having a plurality of small upwardly 80 directed outlets or discharge openings, a delivery pipe of smaller diameter extending upwardly through said stand-pipe its open upper end terminating short of the closed upper end of said stand-pipe but above the 85 normal water level of the tank, a downwardly extending passage being provided by said stand-pipe between its walls and the exterior of said delivery pipe, a circulating supply pipe, a pump mechanism connected in the line of said supply pipe, means for driving said pump mechanism, the intake end of said supply pipe communicating with the upper end of the interior of said tank, the outlet end of said supply pipe 90 communicating with the lower end of said delivery pipe, a heating-coil connected in the line of said supply pipe on the outlet side of said pump-mechanism, a heating-unit mounted beneath said heating-coil, a water pipe connected with said supply pipe on the intake side of said pump mechanism, the intake end of said water pipe communicating with the lower end of said tank, a two-way valve located at the juncture of said water 95 pipe with said supply pipe, and a cover-member for closing the open upper end of said tank.

In testimony, that I claim the invention set forth above I have hereunto set my hand 110 this 2nd day of February, 1916.

ANDREW L. HATFIELD.
